Primary Examiner — S. Bryan Reinholdt, Jr.*Assistant Examiner* — Kaitlan Walker(74) *Attorney, Agent, or Firm* — F. Wayne Thompson, Jr.; Asgaard Patent Services, LLC(57) **CLAIM**

The ornamental design for an inline flashlight mount, as shown and described.

DESCRIPTION

FIG. 1 is a top isometric view of an inline flashlight mount showing my new design;

FIG. 2 is a bottom isometric view of the inline flashlight mount shown in FIG. 1;

FIG. 3 is a left side view of the inline flashlight mount shown in FIG. 1;

FIG. 4 is a front view of the inline flashlight mount shown in FIG. 1;

FIG. 5 is a right side view of the inline flashlight mount shown in FIG. 1;

FIG. 6 is a rear view of the inline flashlight mount shown in FIG. 1;

FIG. 7 is a top view of the inline flashlight mount shown in FIG. 1; and,

FIG. 8 is a bottom view of the inline flashlight mount shown in FIG. 1.

The broken lines represent portions of the inline flashlight mount that form no part of the claimed design.
